CLAIM

The ornamental design for an automobile hitch cover, as shown and described.

DESCRIPTION

FIG. 1 shows a front view of an automobile hitch cover incorporating the design of the present invention;

FIG. 2 shows a front, upper left perspective view of the hitch cover of FIG. 1.

FIG. 3 shows a rear view of the hitch cover of FIG. 1;

FIG. 4 shows a bottom right perspective view of the hitch cover of FIG. 1; and,

FIG. 5 shows a left side view of the hitch cover of FIG. 1, the right side being substantially a mirror image thereof.
